Assistant Examiner — Michelle Marquart Christeon

(57)

CLAIM

The ornamental design for syringe cap as shown and described.

DESCRIPTION

1. Syringe cap
2. Syringe cap
3. Syringe cap
- 1.1 : Front
- 1.2 : Left
- 1.3 : Back
- 1.4 : Right
- 1.5 : Perspective
- 1.6 : Top
- 2.1 : Front
- 2.2 : Left
- 2.3 : Back
- 2.4 : Right
- 2.5 : Perspective
- 2.6 : Top
- 3.1 : Front
- 3.2 : Left
- 3.3 : Back
- 3.4 : Right
- 3.5 : Perspective
- 3.6 : Top
